DESIGN FOR LACE

Jean Dognin, New York, N. Y.

Application November 2, 1936, Serial No. 65,638

Term of patent 3½ years

To all whom it may concern:

Be it known that I, Jean Dognin, a citizen of France, residing in Manhattan, county of New York, and State of New York, have invented a new, original, and ornamental Design for Lace, of which the following is a specification, reference being had to the accompanying drawing, forming part thereof, wherein,

The figure is a plan view of a piece of lace showing my new design.

I claim:

The ornamental design for lace, substantially as shown.

JEAN DOGNIN.
